(57) CLAIM

The ornamental design for a nursing bib, as shown and described.

DESCRIPTION

This application is related to Ser. No. 29/149,248 and to an application entitled shoulder bib, filed of even date with the present application.

FIG. 1 is a perspective view of a nursing bib showing my new design;

FIG. 2 is a front elevational view thereof;

FIG. 3 is a top plan view thereof, with the bib as if spread out on a flat surface; and,

FIG. 4 is an environmental view, showing the novel bib as it would be worn.

The broken line showing of a person in FIG. 4 is for illustrative purposes only and forms no part of the claimed design.
